(57) The ornamental design for a tie hanger, as shown and described.

DESCRIPTION

FIG. 1 is a front, top, right perspective view of a tie hanger showing my new design therefor;

FIG. 2 is a rear, bottom, left perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a view similar to FIG. 1 showing a second embodiment of my invention;

FIG. 10 is a view similar to FIG. 2 thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top plan view thereof; and,

FIG. 16 is a bottom plan view thereof.

The broken lines in FIGS. 9-12, which define the bounds of the claimed design, form no part thereof.
